US0D1043651S

(12) **United States Design Patent** (10) Patent No.: **US D1,043,651 S**
(45) Date of Patent: ** Sep. 24, 2024

(54) **MOUNTING ACCESSORY**

(71) Applicant: **Apple Inc.**, Cupertino, CA (US)

(72) Inventors: **David Kleeman**, Long Beach, CA (US); **Tom Kwon**, Redondo Beach, CA (US); **Mohammadali Parsian**, San Mateo, CA (US); **Peter Schmidt**, Los Angeles, CA (US); **Oliver Seil**, Long Beach, CA (US); **Mitchell Suckle**, Long Beach, CA (US); **John Wadsworth**, Burbank, CA (US)

(73) Assignee: **Apple Inc.**, Cupertino, CA (US)

(**) Term: **15 Years**

(21) Appl. No.: **29/862,094**

(22) Filed: **Dec. 6, 2022**

(51) LOC (14) Cl. **14-06**

(52) U.S. Cl.

USPC **D14/251**; D13/108

(58) **Field of Classification Search**

USPC ..... D14/144, 203.2, 217, 250-253, 447; D13/108; D12/114, 223, 415; D3/218 CPC F16M 13/00; F16M 2200/00; B60R 11/02; H04M 1/12; H04M 1/04; H04M 1/11; A45F 2200/0516; A47B 2023/049; A47B 2097/005; A45C 1/06; A45C 2011/002; B62J 11/00

(57) **CLAIM**

The ornamental design for a mounting accessory, as shown and described.

DESCRIPTION

FIG. 1 is a front perspective view of a mounting accessory showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the mounting accessory which form no part of the claimed design.

1 Claim, 5 Drawing Sheets
